United States Patent Office

Des. 231,096
Patented Apr. 2, 1974

231,096

PALLET

William D. Adam, 31500 1st St.,
South Laguna, Calif. 92677

Filed Mar. 23, 1973, Ser. No. 344,274

Term of patent 14 years

Int. Cl. D9—99

U.S. Cl. D14—3 N

FIG.1

FIG.2

FIG.3

FIG. 4

FIG. 5

FIG. 1 is a perspective view of a pallet showing my new design;

FIG. 2 is a side elevational view thereof;

FIG. 3 is an end elevational view thereof;

FIG. 4 is a top plan view thereof; and

FIG. 5 is a bottom plan view thereof.

I claim:

The ornamental design for a pallet, substantially as shown.
